VALVE-ACTUATING MECHANISM FOR CARBID-RECEPTACLES.

1,130,906.

Specification of Letters Patent.

Patented Mar. 9, 1915.

Application filed July 28, 1914. Serial No. 853,780.

To all whom it may concern:

Be it known that we, JOHN A. JOHNSON and THEODORE N. JOHNSON, citizens of the United States, residing, respectively, at 5 Crawfordsville and Waveland, in the county of Montgomery and State of Indiana, have invented certain new and useful Improvements in Valve-Actuating Mechanism for Carbid-Receptacles, of which the following 10 is a specification.

This invention relates to a certain mechanical device for actuating the valves for discharging carbid from the carbid-receptacles into the generating chambers of acetylene gas generators; and the object of the 15 invention is to provide a mechanical construction for the operation of the valves above noted which will be simple in construction and efficient in operation.

20 A further object of the invention consists in the provision of a simple mechanical construction for actuating valves in carbid-receptacles for acetylene gas generators in which the application of power for actuating 25 the valves is equally applied to the opposite sides so that free and easy actuation of the valves is maintained at all times and lateral strains, which generally interfere with the movements of the parts, will be 30 eliminated.

We accomplish the above objects of the invention by means of the construction illustrated in the accompanying drawings, forming a part hereof, in which—

35 Figure 1 is a central vertical section through the carbid holding receptacle, showing the valves and valve operating mechanism in operative position. Fig. 2 is an underside plan view of the casting forming the 40 upper part and top of the carbid-receptacle, this view being on a considerably reduced scale from that shown in Fig. 1.

45 Referring to the drawings, the carbid-receptacle comprises a hollow cylinder 10, usually formed of sheet metal, the lower end of said cylinder engaging the outer periphery of the upper end of a conically-shaped bottom 11, which bottom is provided with a discharge opening 12. The upper end of the cylinder 10 surrounds the outer periphery of the upper casting 14, which not only forms a bearing for the casting at the top, but the casting 14 also provides a top 15 for inclosing the upper end of the cylinder 10. The space within the cylinder 10

between the top 15 and the bottom 11 provides a receptacle for holding carbid which is fed through the discharge opening 12, in the bottom 11, into the generating chamber of the apparatus at proper times. The discharge opening 12 is kept normally closed by means of a conically-shaped valve 16, arranged exteriorly of the carbid-receptacle, and said valve 16 is mounted upon a valve-rod 17 which extends vertically and centrally through the carbid-receptacle. The upper end of the valve-rod 17 passes through an aperture 18 in the top 15 and to the outside of the receptacle, and the said upper end of the valve-rod 17 is enlarged, as at 19, to provide an offset or shoulder 20 which provides a bearing-seat for a spring 21. The spring 21, at its upper end bears against said shoulder 20 and its lower end bears upon the U-shaped hanger 22, the strength 25 of said spring being merely sufficient to resist the action of gravitation of the valve-rod 17 and the valve 16 and thus keep the valve 16 normally seated within the discharge opening 12. A second protection 30 valve 25, located within the carbid-receptacle, surrounds the valve-rod 17 and protects the discharge opening 12 from above. The valve 25 has vertical movement independent of the valve-rod 17 effected by 35 means of a hollow tube 26 which is threaded into an aperture 27 which affords a free passage for the valve-rod 17 through the center of the valve 25. The tube 26 is provided on its upper end with an annular horizontally 40 projecting flange 30 to be engaged by suitable lifting levers for lifting the valve 25 in a vertical direction. The valve 25 is of metal, and as shown possesses considerable weight so that under normal conditions the lower edge of said valve 25 would be normally kept in contact with the interior surface of the conically-shaped bottom 11. The lower end of the valve 25 is recessed with 45 walls tapering toward the lower edge, whereby a knife-edge formation is provided for severing lumps of carbid that may engage the edge of said valve. This construction of the valve 25 means that it will always be properly seated and in contact with the bottom 11 when occupying its lowest position. As heretofore stated, the valve 25 has 50 vertical movement, which movement is imparted through the tube 26 by means of a pair of lifting levers 35 which are arranged

on opposite sides of and project beneath the annular flange 30 on the tube 26. The levers 35 are mounted on transverse shafts 36 which have bearings in the parallel ribs 37, depending from the top 15 of the casting 14, and the outer ends of the levers 35 pivotally engage the curved ends of the hanger 22.

The operation of the device is as follows: The valve-rod 17 is depressed, either manually, or by means of the lowering of the gas bell, which is common to acetylene gas generators, which unseats the valve 16 from the discharge opening 12. Downward movement is also imparted to the hanger 22 which depresses the outer ends of the levers 35, causing the inner ends of the levers to travel upwardly in the opposite direction. This upward movement elevates the tube 26 and the valve 25, allowing the carbid within the carbid-receptacle to flow freely through its discharge opening 12 into the generating chamber until sufficient gas has been generated to remove the pressure of the gas bell, or other device for actuating the valve-rod 17, when the valve 16 will immediately close the discharge opening 12 and cut off the flow of carbid. The pressure having been removed from the upper end of the valve-rod 17 also allows the hanger 22 to move upward and instant lowering of the valve 25 into contact with the bottom 11, so that continued movement of the carbid toward the discharge opening 12 and valve 16, which might accidentally unseat said valve 16, is effectually cut off.

The movements of the valves 16 and 25 in opposite directions, to regulate the flow of carbid through the discharge opening 12, are induced, first, by the tendency of the spring 21 to expand, after being depressed, which forces the valve-rod 17 up and the hanger 22 down and, second, by taking advantage of the action of gravitation of the heavily weighted valve 25.

To prevent the mass or volume of carbid within the carbid receptacle from impinging and interfering with the movements of the valve 25 and the tube 26, said valve and tube are protected by means of a hollow hood 40 and hollow tube 41. The lower edge of the hood 40, where it contacts the bottom 11, is provided with a plurality of notches 42 to form passageways for the carbid, in its movement toward the discharge opening 12, and the hood 40 is of sufficient vertical length to prevent interference with the vertical movement of the valve 25.

As shown in Fig. 2 of the drawings, the top 15 is provided with suitable openings 43 and these openings are covered by means of doors 45 whereby access may be had to

the interior and for filling the carbid-receptacle.

While we have described our said invention with more or less minuteness as regards details of construction and arrangement and as being embodied in certain precise forms, we do not desire to be limited thereto unduly or any more than is pointed out in the claims. On the contrary, we contemplate all proper changes in form, construction, and arrangement, the omission of immaterial elements, and the substitution of equivalents as circumstances may suggest or necessity render expedient.

We claim:

1. The combination, with a carbid holding receptacle having a discharge opening, of a valve mounted externally of said receptacle for sealing said opening from below, a valve-stem extending vertically through said receptacle for actuating said valve, means for holding said valve to normally close the said discharge opening in said receptacle, a secondary valve arranged within said receptacle for sealing said discharge opening from above, a hollow tube surrounding the valve-stem for actuating the secondary valve, lifting-means engaging the opposite sides of the hollow tube for applying a uniform lifting force to the opposite sides of said hollow tube, means engaging and uniformly actuating said lifting means when the valve-stem is depressed.

2. The combination, with a carbid holding receptacle having a discharge opening, of a valve mounted externally of said receptacle for sealing said opening from below, a valve-stem extending vertically through said receptacle for actuating said valve, means for holding said valve to normally close the said discharge opening in said receptacle, a secondary valve arranged within said receptacle for sealing said discharge from above, means extending parallel with said valve-stem for actuating said secondary valve, a flange around the upper end of said parallel means, lifting-means for applying a uniform lifting force to the opposite sides of said flange, means for connecting and uniformly actuating said lifting-means to cause the secondary valve to move upwardly when the valve-stem and its valve are depressed.

In witness whereof, we have hereunto set our hands and seals at Crawfordsville, Indiana, this 23rd day of July, A. D. one thousand nine hundred and fourteen.

JOHN A. JOHNSON. [L.S.]
